UNITED STATES PATENT OFFICE.

JOSEPH M. EDGAR, OF ARGENTINE, KANSAS, ASSIGNOR TO JOHN Z. RORABACK, OF KANSAS CITY, MISSOURI.

LOCK.

SPECIFICATION forming part of Letters Patent No. 399,189, dated March 5, 1889.

Application filed May 29, 1888. Serial No. 275,484. (Model.)

To all whom it may concern:

Be it known that I, JOSEPH M. EDGAR, a citizen of the United States, residing at Argentine, in the county of Wyandotte and State of Kansas, have invented certain new and useful Improvements in Locks; and I hereby declare the following to be a full, clear, and exact description of the same.

My invention relates to an improvement on the safety-lock for which Letters Patent of the United States No. 352,085 were granted me on the 2d day of November, 1886; and it is designed to serve the same general purpose as the device patented as aforesaid—namely, that of a lock in the sense of a guard on freight-car doors and the like, tending to prevent access to the contents of the car by presenting indication of any tampering with the lock.

In the main the construction of the safety-lock forming the subject of my present application is the same as that shown in my aforesaid patent, the difference consisting, principally, in providing improved means (instead of the pivotal bolt and parts connected therewith) for actuating the registering mechanism in unlocking the device; whereby it changes the combination of characters, and thus indicates the fact of tampering.

The object of my present improvement is to simplify the means for actuating the registering mechanism and for locking it in its set position, thereby, also, to afford better means for the purpose, and, besides, to adapt the device to permit the use with it of an ordinary car-seal formed with a frangible metal strip or with wire, thereby still further to protect it against tampering.

My invention consists in the general construction of my improved safety-lock; and it further consists in details of construction and combinations of parts.

In the drawings, Figure 1 shows my improved device in elevation as applied to the door of a freight-car to prevent access to the interior of the car without unlocking the pivotal bolt (and thereby changing the combination on the registering mechanism) to permit removal of the pivotal bolt from engagement with a staple for the purpose of allowing the hasp to be withdrawn from its locking position over the staple. Fig. 2 presents a similar view of the device with the top plate removed

to disclose the internal mechanism. Fig. 3 is a section taken on the line 3 of Fig. 2 and viewed in the direction of the arrow, Fig. 4, 55 a section taken on the line 4 4 of Fig. 2 and viewed in the direction of the arrows, and Fig. 5 a bottom plan view of the sliding-bolt device for locking and unlocking the pivotal bolt and for actuating the registering mechanism in the unlocking operation to change the combination.

A is the case, having a cover, r , provided with openings r' and with beveled lugs (not shown) on its under side.

B and B' are rotatory disks on stationary shafts extending from inclined lugs (not shown) on the base of the case, on which lugs the disks are supported, whereby they are inclined, as illustrated, and overlap each other. 70 The disks are provided circumferentially on their upper surfaces with numerals, which may range from 0 to 9, and on their lower faces each with a circular flange, separated to leave a lip, and spaces, one on each side of 75 the lip, and directly behind the lip is a lug or projection in radial line with the numeral 9. The disk B is provided in its periphery with teeth q , corresponding in number with the number of numerals on its surface; and each 80 disk B' is provided on its surface about the axis of its rotation with pins or projections q' , corresponding in number with the number of numerals on the disk, each pin being in radial line with a different numeral.

At each opening r' a numeral coincident with it on a disk is displayed. A complete revolution of the disk B, whereby each numeral upon it is in turn brought coincident with the respective opening r' , turns the adjacent disk B' to bring coincident with the respectively-adjacent opening r' a numeral next to that previously displayed, and a complete revolution of the said disk B' turns the adjacent disk B' in the same way, and so on 95 to the end of the series of disks. Thus each time the disk B is actuated the combination of numerals on the series of disks is changed; and it is the means, hereinafter described, for actuating the disk B, and through it the other 100 disks, as described, to which my improvement especially relates.

The parts thus far described and their manner of operation are, by preference, iden-

tically the same as set forth in my aforesaid Letters Patent; hence it is not necessary to show and describe them and set forth their operation more explicitly in the present connection.

The cover *r* is flanged around its edge on the under side, as shown at *p*, Fig. 4, to render it hollow, and toward its upper edge it is provided transversely with a slot, *o*. Adjacent to the slot *o* in the upper right-hand expanded corner (the location being designated with the cover in position, as shown in Fig. 1) is a rounded or cylindrical opening, *n*, leading into a slot, *m*, below it and lengthwise of the cover, and between the extremity of the said cover and the slot *m*, and below the opening *n*, the flange *p* is recessed, as shown at *l*, Fig. 4, a smaller recess, *k*, being also provided in the flange *p* to the left of the corner hereinbefore referred to.

The parts of the case *A* which, when the cover is in position, coincide with the parts thereof thus described are provided, respectively, with a rounded opening, *n'*, leading into a slot, *m'*, and a recess, *k'*, in the upper edge of the case. Thus, when the cover is in place, the opening *n'*, slot *m'*, and recess *k'* coincide with and form extensions of, respectively, the opening *n*, slot *m*, and flange-recess *k*.

Between the upper end of the case and the disk *B* is a chamber, *i*, defined by lugs *i'* or any suitable partition, and adapted to receive and contain a sliding bolt, *C*, reduced toward one end, as shown at *h*, from a shoulder, *x*, and having the reduced part *h* grooved transversely, as shown at *n*, to coincide with the rounded or cylindrical opening *n n'* when the bolt *C* is in its normal or locking position, hereinafter described. On its under and inner side the main or body portion of the bolt *C* is hollowed or chambered out, as shown at *x'* in Fig. 5, and provided near opposite extremities of the chamber with studs or posts *g* and *f*, upon which, respectively, are confined a leaf-spring, *g'*, and a dog, *f'*, extending toward the spring, and against the back of which the spring presses. From the upper side of the bolt *C* extends a stud, *e*. When the sliding bolt is adjusted in the chamber *i* and the cover *r* is in place, the dog *f'* is forced into engagement with the toothed periphery of the disk *B*, and the stud *e* extends through the slot *o*, which corresponds in length, substantially, at least, with the limits of play of the sliding bolt in its chamber *i*.

D is the pivotal curved bolt of the device for the suspension of the latter, hinged at one end to the corner of the case, as shown, opposite that provided with the slot, recesses, &c., as hereinbefore described, and reduced toward its opposite end, as shown at *d*, Fig. 2, which extends through the recess *k k'* when the pivotal bolt is turned into position to be locked, and the inner edge of the part *d* of the curved bolt is recessed, as shown at *c*, Fig. 3, where it coincides with the flange-recess *l* in the

cover to receive the reduced end *h* of the bolt *C* when extended through it.

As shown in Figs. 1 and 2, the device is locked, since the bolt *C* extends through the recess *c* in the pivotal bolt *D* (thereby preventing the latter from being turned to raise it, and thus permit it to be removed from the staples to release the hasp *s*) and through the recess *l*, wherein it may be secured by a tin-strip seal passed through the slot *m m'*, and fastened in the usual manner, or a wire seal passed through the opening *n n' n*. To release the bolt *D*, the bolt *C* must be slid back, which may be accomplished by pressure upon the stud *e*, whereby the bolt *C* is drawn entirely into the chamber *i* and out of engagement with the bolt *D* at the recess *c* therein. The release of the bolt *D* in the manner described, however, necessarily turns the disk *B*, owing to the engagement of the spring-dog *f'* therewith, and each sliding back of the bolt *C* sufficiently far (which is to the limit of its play in one direction and about equal to the distance between two teeth, *q*) to release the bolt *D* thus produces the display of a different numeral on the disk *B*, and changes the combination of the registering mechanism.

A spring-detent, *f*, prevents turning of the disk *B* (and consequently of the other disks of the registering mechanism) by the friction of the spring-dog *f'* against the periphery in returning the sliding bolt to its locking position.

If desired, instead of or besides employing a stud, *e*, as the accessible means for sliding the bolt *C*, obviously the device may be adapted to have the bolt locked and actuated by any suitable form of key removable from the lock into which it fits.

What I claim as new, and desire to secure by Letters Patent, is—

1. In a safety lock or guard for freight-car doors and the like, having a case provided with registering mechanism, substantially as described, the combination, with the case and registering mechanism, of a pivotal bolt, *D*, a sliding locking-bolt, *C*, engaging with the bolt *D* and registering mechanism, and an opening extending through the case and sliding bolt, with the latter in its locking position to admit a car-seal, substantially as set forth.

2. In a safety lock or guard for freight-car doors and the like, having a case provided with registering mechanism, substantially as described, the combination, with the case and registering mechanism, of a pivotal bolt, *D*, a sliding locking-bolt, *C*, engaging with the registering mechanism and bolt *D*, a slot, *o*, in the cover of the case, and a stud, *e*, on the bolt *C* extending through the slot *o*, substantially as set forth.

JOSEPH M. EDGAR.

In presence of—

H. KESSLER,

W.M. GEGUS.
